UNITED STATES PATENT OFFICE

132,746

DESIGN FOR A RECORD HOLDER FILE

Jack E. Schenker, Chicago, Ill.

Application March 7, 1942, Serial No. 106,115

Term of patent 14 years

To all whom it may concern:

Be it known that I, Jack E. Schenker, a citizen of the United States, residing at Chicago, in the county of Cook and State of Illinois, have invented a new, original, and ornamental design for a Record Holder File, of which the following is a specification, reference being had to the accompanying drawing, forming a part thereof.

In the drawing:

Fig. 1 is a perspective view of a record holder file in open position showing my new design; and
Fig. 2 is a perspective view of the same closed.

I claim:

The ornamental design for a record holder file, as shown.

JACK E. SCHENKER.
